(57) **CLAIM**

The ornamental design for a mobile phone, as shown and described.

DESCRIPTION

FIG. 1 is a front perspective view of a mobile phone showing my design.

FIG. 2 is a rear perspective view of the mobile phone in FIG. 1.

FIG. 3 is a front elevation view of the mobile phone in FIG. 1.

FIG. 4 is a rear elevation view of the mobile phone in FIG. 1.

FIG. 5 is a left side elevation view of the mobile phone in FIG. 1.

FIG. 6 is a right side elevation view of the mobile phone in FIG. 1.

FIG. 7 is a top plan view of the mobile phone in FIG. 1.

FIG. 8 is a bottom plan view of the mobile phone in FIG. 1; and,

FIG. 9 is an enlarged view of a portion of the mobile phone labeled 9 in FIG. 1.

The broken lines in the drawings are employed to show unclaimed portions of the mobile phone, and form no part of the claimed design.

1 Claim, 9 Drawing Sheets
